UNITED STATES PATENT OFFICE.

GEORGE L. LAWRENCE, OF MELROSE, MASSACHUSETTS.

METHOD OF MANUFACTURING OVERSHOES.

Original application filed June 14, 1927, Serial No. 198,709. Divided and this application filed February 14, 1928. Serial No. 254,307.

My present invention relates to overshoes, and more particularly to a novel and improved method of manufacturing overshoes, and is a division of my prior and copending 5 application Ser. No. 198,709, filed June 14, 1927.

While I have illustrated the present invention as applied to overshoes of the cuff type, it will be appreciated that my novel 10 process is equally applicable to other types of overshoes, such as the one-buckle type of overshoes, where the outside upper material may be laminated with fleece or other lining, and buckles utilized in place of straps. My 15 construction will apply equally well to high gaiters or overshoes, as well as to the well-known types of rubbers.

The usual prior method of manufacturing overshoes has been to last up a lining to an 20 insole and filler, then apply a toe strip, counter, heel piece, and the like, then to provide a quarter, usually provided with a pocket, and a vamp, and to last these over the lining with its component parts already assembled, and then to apply a foxing and outsole. In some instances this process has been 25 varied by assembling some of the cut-out parts beforehand, viz., assembling them flat, but the structure of the completed overshoe has 30 been invariably the same, and such process has also required the separate handling of the separate pieces or sections of the upper materials.

An important object of my present invention 35 is the provision of an overshoe which will be light in weight, much more so than present overshoes, which will be much neater and more comfortable because of the absence of seams inside of the overshoe, and which 40 will present an extremely material saving in cost due to the elimination of handling of some of the upper portions, and the entire elimination of other portions, such as the pocket portions, separate cuff, toe strip, back 45 stay and quarter stays.

A further object of the present invention resides in that step during the method of manufacture which consists in uniting the 50 vamp and quarter by stitching, thus insuring a rugged and durable overshoe.

Another object of the invention is to first 55 laminate, preferably in sheet or strip formation, the materials from which the quarter and quarter lining, vamp and vamp lining

are cut or formed. This lamination can be 55 carried out in different manners. For example, a sheet or roll of the fabric which is used to form the outside of the gaiter or overshoe is coated with rubber compound on a calendar. Then a sheet or roll of the fabric 60 or material to be used for the lining and cuff is similarly coated on a calendar. These two sheets of stock are then laminated together with the rubber coatings adhering to produce a sheet or roll of material with the outside 65 upper material on one side and the lining material on the other side, with the rubber therebetween. An optional method of lamination would be to prepare this double sheet of material at one operation, which could 70 be performed by running the two sheets of material into a calendar with a sheet of rubber interposed therebetween and pressing together at one operation.

A further object of the present invention 75 consists in constructing an overshoe in which the united vamp and vamp lining are so folded as to form pockets, but without the addition or insertion of separate pocket forming portions.

A further object resides in so cutting and uniting the quarter and vamp that the quarter 80 and its lining will extend above the normal height of the overshoe for a sufficient distance to permit the same to be turned to form 85 an integral cuff, the exposed surface of said cuff thus being preferably of the same material as the quarter lining.

Another object is to continue the stitching 90 which unites the vamp and quarter completely around that portion of the quarter and its lining which constitutes the cuff forming portion.

A further object of the invention resides 95 in that step during the process of manufacture which consists in applying a counter, or a combined counter and heel piece outside of the upper materials, instead of inside or between the upper materials as has been the usual practice heretofore. I preferably 100 form this combined counter and heel piece in the same manner as described for the preparation of the laminated vamp and quarter, viz., by assembling two sheets of material, representing the counter side and heel piece 105 side, and then cutting or dieing the combined counters and heel pieces therefrom. This eliminates the handling of the heel piece as

a separate unit, and if desired, said counter may be affixed to the upper materials before lasting.

A further object consists in forming the vamp of sufficient depth or length that it can be lasted over onto an insole without the addition of separate toe strips.

It will thus be seen, that in manufacturing my novel overshoe, I eliminate the separate handling of eight separate pieces, viz, vamp lining as a separate piece; quarter lining as a separate piece, cuff, back stay, heel piece as a separate piece, toe strip, and two quarter stays. It will be readily appreciated that this reduction in the number of pieces to be handled will materially decrease the labor required to produce my novel overshoe, as well as materially decreasing the cost of same, and reducing the weight of the completed overshoe, besides resulting in a much neater and better fitting overshoe.

My novel method of manufacture is simple, rapid, economical and highly efficient, in that it produces an overshoe possessing features and qualities not possible in prior methods of manufacture.

I believe that the process of manufacturing overshoes, as above briefly described, and as hereinafter more fully explained, is novel, and I have therefore claimed the same broadly in the present application.

The above and other features and objects of the invention, details of construction, combinations of parts, and advantages, will be hereinafter more fully pointed out and claimed.

Referring to the drawings, illustrating a preferred embodiment of the present invention,

Fig. 1 is an elevation of a laminated sheet of material from which the vamps and quarters and their respective integral linings are to be cut or died;

Fig. 2 is a front elevation of the vamp as cemented;

Fig. 3 is a front elevation of the quarter as cemented;

Fig. 4 is a front elevation of the vamp and quarter united by stitching;

Fig. 5 is a rear elevation of the united quarter and vamp illustrating the attachment of the buckle strap and snaps, and stitching of the back seam;

Fig. 6 is a cross-sectional view, on an enlarged scale, of the laminated upper materials lasted over an insole and up to a filler;

Fig. 7 is a cross-sectional view illustrating the next step, viz, that of applying a counter and heel piece, and with or without a second filler;

Fig. 8 is a longitudinal sectional view illustrating the application of the heel foxing and toe foxing;

Fig. 9 is a longitudinal sectional view illustrating the application of the outsole; and

Fig. 10 is a side elevation of a completed overshoe, also illustrating the outsole after corrugating or rolling.

Referring now to the drawings, for a particular description of my novel method, and the various steps involved in carrying out the same, I first prepare a laminated sheet or strip consisting of a layer of material 1 to be utilized for the outside of the upper materials, and a layer of material 2 to be utilized for the lining. This laminated sheet may be formed in different manners, either by coating each of the layers 1 and 2 with rubber compound and then adhering the coated surfaces, or by running the two layers 1 and 2 through a calendar with a sheet of rubber interposed therebetween. These methods of lamination are optional.

From this laminated sheet I then cut two pieces for each shoe, viz, the vamp 3 and the quarter 4, any desired plurality of these quarters and vamps being cut from the laminated sheet. They may be cut out singly, or in gangs, as illustrated in Fig. 1, by the use of suitable cutting dies.

Each of the two upper pieces, vamp 3 and quarter 4, is thus composed of two pieces of identical size and shape, securely unified.

The quarter 4 is provided with a slit as at 5 to enable the heel portion of the quarter to be fitted. The vamp 3 is provided with a pair of projecting tabs or ears 6, the purpose of which will be hereinafter explained.

As the next step in my novel process I then apply a narrow margin of cement on the inside bottom edge of each of the vamp and quarter, as illustrated at 7 on the vamp and 8 on the quarter. I also cement the outside bottom of said vamp and quarter, as illustrated at 9 on the vamp and 10 on the quarter, this outside cementing being of greater width than the inside cementing for the purpose of receiving the foxing on the vamp, and the counter and foxing on the quarter. I have illustrated this cementing operation as being performed at this point during the process of manufacture, since the application of the cement is facilitated by having the two upper portions, vamp and quarter, separate, but it will be appreciated that this cementing can be performed later, after the two portions are united, if desired.

As the next step, I apply the vamp to the quarter in such manner that their edges will be aligned, the quarter 4 being of greater width than the vamp 3, as illustrated. The quarter 4 is so constructed that a portion 11 thereof will project above the top of the vamp when the two are assembled. The ears or tabs 6 are bent around the bottom corners of the quarter and adhered thereto, as illustrated at 12. Stitching 13 is then applied, this stitching preferably starting at the point marked by the ear 6 on one side, and continuing upwardly and uniting the edges of the vamp 3 and quar-

ter 4, then continuing around the portion 11, both to insure against fraying of the laminated quarter, and down the opposite side, uniting the edges of the vamp and quarter on that side, and preferably ending at the tab or ear 6, or at about the point where the top of the foxing will come. This stitching 13, which is preferably overcast, of course, can be continued to the bottom of the united vamp and quarter if desired, but this is optional. This union of the vamp and quarter by the stitching 13 results in a rugged overshoe construction, possessed of great strength.

If desired, a small staple can be applied at the beginning and end of the stitching, but this is also optional.

I then insert snap fasteners 14, any desired number of the same being utilized, and apply a strap 15 and snap 16 for such fasteners, this strap 15 being secured by stitching 17 or in any other desired manner. The edges of the slit 5 are also brought together and united in any desirable way, as by stitching 18, as illustrated, or by piping, or simply being overlapped, if desired.

These two united pieces, viz, vamp 3 and quarter 4, form the entire upper, which is now ready for lasting.

In Fig. 6 the quarter 4, with its integral lining 19, is illustrated lasted over an insole 20, on a last 21, and up to a usual filler 22, the edges of the upper materials abutting against the edges of the filler as at 23. If desired, the filler 22 and insole 20 may be formed as a unit before application to the last, this being an optional method of construction.

Onto the heel of the cemented portion 10 of the quarter is then applied a counter 24, preferably a combination counter of a friction fabric and a stiffening stock, thus comprising two layers, as shown at 24 and 25. This combination counter may be cut from laminated sheets prepared beforehand in a similar manner to the upper materials, if desired. While I have illustrated herein a second filler 26, with the edges of the counter overlapping the same, I may, if desired, unite the counter with the quarter before lasting, and dispense with the second filler. To the cemented portion of the vamp I then apply a toe foxing 27, preferably of rubber, and over the counter I apply a heel foxing 28, also preferably of rubber. The overshoe is now ready for the application of the outsole 29, as shown in Fig. 9, which outsole, after attachment, is preferably rolled to corrugate the same, as at 30, as is usual.

In Fig. 10 is illustrated the completed overshoe, with the cuff 11 turned down.

The vamp is folded upon itself to form pockets, as at 31, to accommodate and fit varying leg sizes.

It will thus be instantly apparent to those skilled in this art that I have devised a novel, simple, rapid and economical method of

manufacturing overshoes. By eliminating the handling of eight pieces, as separate units during the process of manufacture, I have considerably reduced the labor and time required to manufacture such overshoes. By completely eliminating several pieces, such as toe strips, back stays and quarter stays, the overshoe is considerably lightened, and also results in a better fitting and more comfortable overshoe. By eliminating the separate pocket forming pieces heretofore utilized, I have still further added to the comfort and ease of fitting of my novel overshoe. The comfort to the wearer is also increased by the feature of applying the counter over or outside of the upper materials, rather than between or inside thereof. I also effect a considerable further saving in material and labor by constructing the lining integral with the quarter and vamp, thus doing away with the trimming of the pockets, and around the top of the overshoe. The cementing of the parts 7, 8, 9 and 10 can be performed efficiently by machine operations.

The smooth unbroken quarter lining, and vamp lining, also present advantages which will appeal to those in this art, as well as to the purchasers and wearers of these overshoes. If desired, that portion of the lining which is to constitute the exposed surface of the cuff, may be formed of a material different in color from the rest of the lining, and many pleasing effects can thus be obtained.

It will also be appreciated that the present invention is equally applicable to overshoes or rubbers of the type wherein the upper materials consist of a single upper piece, instead of quarter and vamp. The invention is also equally applicable to other types of overshoes, whether of the high type, one buckle type, or others.

While the invention has been necessarily described somewhat in detail, it will be appreciated that the same may be varied within reasonably wide limits without departing from the spirit of the invention.

My invention is further described and defined in the form of claims as follows:

1. The improved method of manufacturing overshoes which consists in uniting a layer of upper material and a layer of lining material, cutting from said laminated sheet upper materials comprising a quarter and quarter lining of identical size, and a vamp and vamp lining of identical size, assembling said quarter and vamp and their respective linings with their side edges alined, uniting said vamp and quarter and their respective linings by stitching along said alined edges, lasting said upper materials onto an insole, applying a counter over said upper materials and under said insole, and completing said overshoes.

2. The improved method of manufacturing overshoes which consists in uniting a layer of upper material and a layer of lining material, cutting from said laminated sheet upper materials comprising a quarter and quarter lining of identical size, and a vamp and vamp lining of identical size, assembling said quarter and vamp and their respective linings with their side edges alined and with a portion of said quarter and lining extending above said vamp to form a cuff, uniting said vamp and quarter and their respective linings by stitching along said alined edges, lasting said upper materials onto an insole, and completing said overshoe.
3. The improved method of manufacturing overshoes which consists in uniting a layer of upper material and a layer of lining material, cutting from said laminated sheet upper materials comprising a quarter and quarter lining of identical size, and a vamp and vamp lining of identical size, assembling said quarter and vamp and their respective linings with their side edges alined and with a portion of said quarter and quarter lining extending above said vamp to form a cuff, uniting said vamp and quarter and their respective linings by stitching along said alined edges,

edges, continuing said stitching entirely 30 around that portion of the quarter and quarter lining which is to form the cuff, lasting said upper materials onto an insole, and completing said overshoe.

4. The improved method of manufacturing overshoes which consists in uniting a layer of upper material and a layer of lining material, cutting from said laminated sheet upper materials comprising a quarter and quarter lining of identical size, and a vamp and vamp lining of identical size, said vamp and lining having a pair of projecting tabs thereon, assembling said quarter and vamp and their respective linings with their side edges alined, adhering said tabs to said quarter at the lower rear corners thereof, uniting said vamp and quarter and their respective linings by stitching along said alined edges, lasting said upper materials onto an insole, 40 folding said vamp and its lining to form pockets without the addition of separate pocket forming pieces, and completing said overshoe.

In testimony whereof, I have signed my 55 name to this specification.

GEORGE L. LAWRENCE.
